UNITED STATES PATENT OFFICE.

JOHN T. HICKS, OF MEDFORD, MASSACHUSETTS.

CANCELING-BOX FOR WAITERS' CHECKS.

No. 909,088.

Specification of Letters Patent. Patented Jan. 5, 1909.

Application filed May 1, 1907. Serial No. 371,208.

To all whom it may concern:

Be it known that I, JOHN T. HICKS, a citizen of the United States, and a resident of Medford, in the county of Middlesex, State 5 of Massachusetts, have made certain new and useful Improvements in a Canceling-Box for Waiters' Checks, of which the following is a specification.

This invention relates to that class of useful devices designed and adapted for use by 10 waiters in a restaurant.

The object of this invention is to provide a device for use by waiters at the so-called "quick lunch" counters where a check is 15 passed from the waiter to the consumer with each article of food served at the time of service.

The rectangular box is provided with a slit at one end through which the card is 20 ejected and a closing device for the opposite end of peculiar and novel construction readily removed and replaced. The box is of sheet metal and the closing device is a strip of resilient metal having two arms of 25 unequal length with projections on each arm engaging sockets in the sides of the box, the spring metal strip and the arms being so arranged that the pressure of the thumb at the center of the strip releases it from the 30 box while under all other circumstances it is tightly locked in position by the engagement of the projections with the sockets.

Between the series of checks and wall of the box is an ejecting device, this consists of 35 a plate having two arms and a thumb piece, the thumb piece is on the exterior of the box connected to the ejector by a pin or rivet passing through a slit in the wall of the box; the edge of this plate remote from the ejecting 40 slit is curved or bent downwards a distance equal to the thickness of one of the checks, when the thumb advances the check the rear end of the ejecting plate with the described curve or bent edge is slightly advanced so that the bent edge follows the 45 check in its initial movement and the ejection of the check is completed by applying the thumb to the thumb piece and moving it forward. By the arrangement described 50 the ejector can only advance one check at a time as the bent edge always rides upon the surface of the second check, after the first check is advanced by the thumb. On the inner wall of the box is fixed a plate section 55 in the path of the ejecting device to block the movement of said device.

The accompanying drawings illustrate the invention.

Figure 1 is a top plan view of the box; Fig. 2 is an end view of the same, part of the 60 interior mechanism shown in dotted outline; Fig. 3 is a top plan view showing a cardboard check partly ejected; Fig. 4 is an end view opposite to that shown in Fig. 2; Fig. 5 is a longitudinal section showing the follower 65 with the actuating spring therefor in dotted outline; Fig. 6 is a cross section; Fig. 7 is a plan view of the bottom of the box; Fig. 8 shows the unequal arm closing devices; Fig. 9 is a side elevation; Fig. 10 is a side elevation 70 opposite to that shown in Fig. 9; Fig. 11 is a longitudinal section; Fig. 12 is a plan and sectional view of the ejector plate-section.

The box or receptacle 20, preferably of 75 sheet metal, is rectangular and its ends are closed by resilient strips of sheet metal 21. These strips have terminal arms of unequal length, the arm *a* in each case being somewhat longer than its companion arm *b*; on 80 each arm *a* and *b* there is a projection 22 tapered from the free end of the arm and suitably shaped to engage an aperture *c* in the wall of the box 20. By pressing upon the center of this strip of spring metal 21, 85 causing it to assume the position shown in Fig. 5, the arms *a*, *b*, are thrown out of engagement with the apertures *c*. The longer arm *a* is thrown out further than the arm *b* and the strip is turned on the arm *b* as a 90 hinge. This unequal length of the arms increases the ease and facility of application and removal of the closing strips.

Within the box 20 are placed a series of 95 superposed cardboard checks *d* having numerals arranged a fixed distance from the edge, shown in Fig. 3 at 23. A plate or follower 24 is placed under this series of checks *d*; the follower is rectangular and about the same in area as the top wall of the box. There 100 is a conoidal, helical spring *s* having its apex in contact with the opposite interior wall of the box and its greatest convolution fixed to the surface of the follower; this arrangement of the spring produces an even and uniform 105 pressure upon all parts of the follower and serves to force the series of checks against the inner wall of the box with uniform pressure. At one end of the box immediately adjacent to the upper wall is an ejecting slit 110 *e*. There is a perforation 25 in the upper wall of the box of sufficient size to receive the

tip of the finger of the operator which is used to initiate the ejection of the upper or outer check of the series through the slit *e*. As shown in Figs. 1, 2, 11, and 12, there is an 5 ejecting plate-section 26, this is bifurcated so as to straddle the aperture 25, at the rear end it has a lip 27 turned down about the thickness of a check. The plate-section 26 has a neck 28 passing through a slot 30 in the 10 upper wall of the box to which neck is fixed a thumb piece 29. By applying the finger to this piece 29 the plate 26 is caused to slide on the under side of the upper wall. As shown in Figs. 3 and 11 there is a plate- 15 section 31 fixed to the upper interior wall of the box; it is bifurcated to avoid closing the aperture 25 and acts as a stop to limit the movement of the plate-section 26. In the operation of ejecting a check the finger is 20 applied to the check through aperture 25, the check is thus partly ejected, the plate-section 26 is advanced until the lip 27 rides on the check immediately below, that is, the second check of the series, and then engages 25 the rear edge of the upper check, completing the ejection to the point where the plate 26 is stopped by the plate 31; this leaves and holds the edge of the check within the box until the check is removed by the hand and 30 placed within the holding device *f*.

The holding device *f* consists of a flat spring strip 33 fixed to the box at 34, the spring strip 33 is bifurcated at 35, 36, and perforated at 37, 38; the arms 35, 36 are 35 resilient and grip and hold the check when it is placed between them. The plane of the spring *f* is at right angles to the ejecting slit, this renders the holding device *f* visible so that the check may be easily inserted 40 between the parts 35, 36, as the box is held with its top upward; fixed to the side wall of the box in line with the perforations 37, 38, is a cutting projection 40, the distance between the perforations 37 and 38 and the 45 junction of the bifurcations 35, 36, is about equal to the distance between the edge of a

check *d* and the line of numerals 23 near the margin so that the perforation of the cutter 40 always occurs at about the same point with respect to the numerals.

At each corner of the bottom wall of the box on the outside are fixed loops 50, these loops are designed to engage the corners of a card, upon which any desired record or notation may be made.

What I claim and desire to secure by Letters Patent is:

1. In a device of the character described, the combination of a box and a cover therefor consisting of a strip of spring metal having two arms of unequal length fixed in parallel planes at opposite ends of the strip, interior projections on said arms and sockets in the opposite walls of the box to receive 60 said projections.

2. In a device of the character described the combination of a box or inclosure having an ejecting slit for a check in the end wall near the upper wall, a perforation in said upper wall to admit the finger of the operator, an ejecting plate section having a projection adapted to engage the rear edge of an adjacent check, said plate having its advanced edge divided, one division being located upon each side of said finger perforation, and a plate section fixed to said upper wall of the box, both said plates having their exposed surfaces in the same plane.

3. In a device of the character described, an inclosing receptacle having an ejecting slit in the end wall near the side wall, a removable cover consisting of a strip of resilient sheet metal having at the ends angular flanges formed with projections adapted to engage perforations in the side walls of the box, said projections having their contacting faces tapered, substantially as shown and described.

JOHN T. HICKS.
